COUPLING FOR SEWER CLEANING RODS

George Burton, Gaston, Ind.

Application November 17, 1936, Serial No. 111,313

1 Claim. (Cl. 287—103)

This invention relates to that classification of structures now generally identified as sewer cleaning rods and has reference in particular to a specifically new type coupling for pivotally and separably connecting the companion rods together.

Removing sewage and clogged matter from sewerage systems through the instrumentality of disconnectable pivotally jointed rod devices, is now common practice. Generally speaking the device is made up of a plurality of wooden sticks of appropriate shape and length, these being separably coupled together at coordinated ends.

The purpose of the present invention, as above implied, is to provide a new type coupling between the wooden sticks or rods, the coupling being made up of complementary male and female members or sections, and these being separably and pivotally joined through the instrumentality of safe, reliable, and simple uniting means.

The precise details relied upon to import structural newness and features of refinement will become more readily apparent from the accompanying drawings and detailed description thereof.

In the drawings wherein like numerals are employed to designate like parts throughout the views:—

Figure 1 is a side or edge elevational view of a sewer cleaning rod assembly or structure embodying the improved couplings constituting the novelty of the present invention.

Fig. 2 is an enlarged close-up elevational view depicting the coupling means with greater particularity.

Fig. 3 is a top plan view of Fig. 2.

Fig. 4 is a sectional and elevational view, the section being taken on the plane of the irregular line 4—4 of Fig. 2.

Fig. 5 is a transverse or cross sectional view on the plane of the line 5—5 of Fig. 3.

Figs. 6 and 7 are elevational or detail views of the companion units or sections of the improved coupling means.

Referring now to the drawings by distinguishing reference numerals, it will be observed that the wooden sticks or rods are denoted by the numerals 8 and these are more or less conventional in design. They are generally rectangular in cross sectional form and of suitable length. The adjacent or proximate ends of the rods are joined together by the companion male and female coupling units or members 9 and 10 respectively of the type shown in Figs. 6 and 7. These coupling units or members are preferably in the

form of aluminum castings. Each casting includes what may be called a channel-shaped portion 11 and the rods are located therein between the side flanges and secured in place by bolts or equivalent fasteners as indicated at 12 in Fig. 5. At one end, the body portion of the section or unit 9 is bifurcated and the furcations are denoted by the numerals 13, these being disposed in spaced parallel order and having therebetween opposed vertical rigid studs or pins 14 and 15 respectively. The body portion of the section 10 is in the nature of a shank shaped and proportioned to fit between the furcations. The shank may be said to be of general rectangular cross sectional form and it is denoted by the numeral 16. In one longitudinal edge is a substantially diagonal notch 17 terminating in a rounded crotch portion forming a seat 18 for the pin 14. On this same side is an appropriately shaped retention hook 19 engageable with the pin. On the opposite side, the extension or shank 16 is formed with a substantially V-shaped notch 20 to receive the retention pin 15. This notch formation in effect defines an abutment or guard finger as at 21, which is engageable also with said pin 15. Thus, by slipping the shank 16 in between the furcations 13 and engaging the hook 19 with the pin 14, this locates the pin 15 in the V-shaped notch 20, and places the finger 21 in a position to insure an appropriate quick releasable connection between the parts 9 and 10.

With this type of a coupling it is evident that the rod 8 can pivot in one direction only, that is it can swing into substantially obtuse angular relationship in one direction only. The association of the lug 21 with the pin 15 prevents angling of the rod in the opposite direction, that is, in a horizontal plane. Incidentally the word "horizontal" is used advisedly, having reference only to the drawings, and particularly Figs. 1, 2 and 4. That is to say, since the device is usable in both horizontal and vertical directions, it is obvious that the description relates to the drawings only.

A coupling of the type specifically described and illustrated is believed to be competent and reliable for the duties to be performed. It possesses requisite stability and is otherwise proportionately efficient to aptly measure up to the requirements of an assemblage of this type.

It is thought that persons skilled in the art to which the invention relates will be able to obtain a clear understanding of the invention after considering the description in connection with the drawings. Therefore, a more lengthy description is regarded as unnecessary.

Minor changes in shape, size, and arrangement of details coming within the field of invention claimed may be resorted to in actual practice, if desired.

5. What is claimed as new is:—

5. A sewer plunging and dislodging device comprising a pair of complementary rods, coupling means separably joining adjacent ends of said rods and comprising male and female coupling units, one unit embodying spaced parallel furcations forming a slot therebetween and having a pair of transverse connecting pins extending therebetween equidistantly spaced from the inner end of the slot, the other unit comprising a

shank for location in said slot, said shank comprising a hook extending between the pins to take over one pin whereby said units are interlocked against endwise separative movement outwardly of each other and swingable relatively in 5 to angular relation, and a finger adapted to bear against the outer side of the other pin to stabilize the hook, said finger cooperating with the inner end of the slot to block relative swinging of said sections in one direction and being swingable 10 around said other pin during swinging movement of the interlocked units in the other direction.

GEORGE BURTON.
